UNITED STATES PATENT OFFICE.

SIMON COOPER, OF NEW YORK, N. Y., ASSIGNOR TO GORTON-PEW FISHERIES COMPANY,
OF GLOUCESTER, MASSACHUSETTS, A CORPORATION OF MAINE.

COMPRESSOR.

1,155,798.

Specification of Letters Patent.

Patented Oct. 5, 1915.

Application filed July 23, 1913. Serial No. 780,627.

To all whom it may concern:

Be it known that I, SIMON COOPER, a citizen of the United States of America, and a resident of New York, in the county of Kings, borough of Brooklyn, and State of New York, (whose post-office address is No. 32 East Twenty-third street, New York, N. Y.,) have invented certain new and useful Improvements in Compressors, of which 10 the following is a specification.

This invention relates broadly to compressors, and more particularly is designed to provide an apparatus adapted to compress into a homogeneous cake or form a material which is capable of mass compression, and which is preferably shredded, flaked or stripped, whether or not such material be preliminarily accommodated within a container; an apparatus the embodiment of which herein disclosed is especially adapted for utilization in connection with the compression or caking of fish products.

The cardinal object of this invention is to provide a compressing instrumentality and 25 controlling means therefor whereby such instrumentality may gradually become effective.

Another object of this invention is to provide such an apparatus, and one further adapted to transport the material to 30 be caked during the pendency of the compressing operation.

A further object of the invention is to provide such an apparatus, and one adapted 35 so to compress said material simultaneously into a plurality of cakes that preferably separate unit masses of material may be successively fed into the apparatus and thereupon each become removed from the 40 point of feeding thereafter to lie adjacent other predetermined points within the apparatus whereby the compressing instrumentality may progressively become more efficient adjacent each successive predetermined point.

Another object of the invention is to provide in connection with such apparatus means adapted to cause a predetermined disposition within such apparatus of such 50 units of the material as have not been properly disposed within the said apparatus adjacent the point of feeding.

Another object of the invention is to provide automatic means for causing a halting

of a certain part of the apparatus upon an engagement of a unit of the material with the means mentioned in the preceding paragraph, provided that such engagement is so established that said means may not perform its characteristic function.

Another object of this invention is to provide in connection with such apparatus means adapted automatically to cause the egress from within range of the effective instrumentalities of each successively fed and predeterminedly finally compressed mass units of material.

Other objects and aims of the invention, more or less broad than those stated above, together with the advantages inherent, will 70 be in part obvious and in part specifically referred to in the course of the following description of the elements, combinations, arrangements of parts, and applications of principles constituting the invention; and 75 the scope of protection contemplated will appear from the claims.

In the accompanying drawings, which are to be taken as a part of this specification, and in which I have shown a form of embodiment of the invention as at present preferred:

Figure 1 is a vertical view, looking toward the feeding point 6, and illustrating said embodiment; Fig. 2 is a top plan view 85 of said embodiment; Fig. 3 is a side elevation, but looking toward the parts disclosed in Fig. 2 in the direction of the arrow 7, this view being partly broken away and partly in elevation for a clearer disclosure of the 90 parts; Fig. 4 is a top plan view of the parts disclosed in Fig. 2, certain of the parts being broken away and certain of the parts not being shown; and Fig. 5 is a vertical sectional view taken on the line 5—5 95 of Fig. 2 and looking in the direction of the adjacent arrows, this view not showing all of the superposed and below parts but disclosing a form of container 8 which may with advantage be utilized in connection 100 with the compression action if desired.

Similar reference characters refer to similar parts throughout the several views of the drawings.

Referring now to the accompanying 105 drawings, reference numeral 9 represents a preferably rigid base or bed-plate, which is provided with a web 10 (Fig. 3) supporting

a central hub or bearing 11 to receive the lower end of the vertical shaft as shown. A revolving table 13 is mounted loosely upon said shaft 12 for revolution thereon, 5 the said table being provided on its underside as shown with bosses 14, tapped to receive bolts 15; these bolts serving to fasten worm gear 16 to said table.

The teeth carried by worm gear 16 are 10 adapted to mesh, as best shown in Fig. 4, with the teeth carried by a worm 17 fixedly mounted upon the main driving shaft 18, the last being driven in the manner herein- 15 after described from the pulley 19 (Fig. 3) and being adapted preferably to be automatically controlled as hereinafter described, through certain clutching means disposed within the clutch case 20 here employed and hereinafter described. Pulley 20 19 is driven from the belt 21, preferably traveling in the direction of the arrow shown thereon in Fig. 3.

On the upper face of table 13 (Figs. 1, 2 and 3) are a plurality of subdivisions or 25 delimited areas 22, which are established by the wedge-shaped pieces 23 equally distanced upon and fastened to said table as shown.

Mounted loosely on said shaft 12, but fastened to said table and rotating with it, is 30 a turret 24 (Figs. 1, 2 and 3), and said turret carries in the manner below described a plurality of sliding pieces or plungers 25, each corresponding to and each opposite one 35 of the subdivisions 22, and each disposed for movement vertically in gibs 26 carried upon the outer face of said turret. On the upper end of each slide 24 is a stud 27, upon which is adapted to be pivotally supported 40 a sliding piece 25, as shown, held in place by a nut 28; and upon each of which studs is loosely mounted for revolution thereon a roller 29.

Each roller 29 is adapted to travel, during 45 the revolution of worm gear 16 and consequently during the simultaneous revolution of turret 24, in the track or groove 30 (Figs. 1 and 3) formed in the outer peripheral surface of the cam 31 which is loosely mounted 50 upon the shaft 12 but fixed against revolution therewith by means of the bolt 32 (Fig. 3) setting up a rigid connection between said cam 31 and the arm 33. As best shown in Fig. 2, said arm is fastened to and supported upon the rear extension 34 of the 55 bed-plate 9. The worm 17 (Figs. 2 and 4) is suitably accommodated within the gear box or pocket 17' rigidly connected as shown to the bed-plate 9, with which box the adjacent terminus of driving shaft 18 is journaled.

Mounted as shown upon each sliding piece 60 25 is a shoe 35. These shoes are capable of preferably slight adjustment in vertical direction by means of the slotted holes 36

(Fig. 1) through which the bolts 37 pass in fastening the shoes to sliding piece 25. The screws 38 (Fig. 3) are here disclosed to prevent any backing of the shoes upon their supporting pieces 25. The under surface of 70 each shoe is here disclosed as constituting a flat rectangular face 35' corresponding in outline with the outline of each shoe 35 shown in Fig. 2, properly disposed to descend within the metal form or container 75 utilized. In the practice heretofore followed, each container is preferably open top and bottom, that is, not yet provided with the floor 8' disclosed in Fig. 5.

A recess 39 is formed in each of the sides 80 of each preferably wedge-shaped piece 23 to receive the beaded lower edges of the container 8 (Fig. 5) and similar recesses 40 are formed in the base of turret 24 for co-operation with said recesses 39. The front end 85 of each shoe 35 carries as shown (Figs. 1 and 3) a preferably beveled and depending nose-piece 41 which predeterminedly assists in forcing the cam 42 (Fig. 2), as will appear from the description hereinafter, into its proper place, and furthermore aids said cam in withstanding any internal pressure caused by the compression of a foot 35 upon the contents of a container, or else has a tendency to keep collected a mass unit of 90 the material itself were not such a container utilized. It will thus be seen that during the revolution in the direction of the arrow shown in Fig. 2 of rotating table 13, and with it the eight subdivisions 22 (into each 95 of which a mass of material or a container 8 predeterminedly filled with said material is adapted to be fed adjacent the feeding point 6 shown in Fig. 2), each of said subdivisions with its load will successively co-operate with and be acted upon by said cam 42 in the manner aforesaid. During the revolution of said table 13, each of said subdivisions, preferably loaded as aforesaid, and each carrying above it in constant vertical relation one of the compression shoes 35, is transported successively past each of the delineated locations 22 shown in Fig. 2; and it will be understood that the lay of the peripheral groove 30 (formed in the cam 31 115 fixedly arranged as illustrated in Fig. 3), which groove is preferably gradually descending between the points 43 and 44 (Fig. 2) and preferably gradually ascending between the points 44 and 43 (Fig. 2), the 120 point 43 being preferably adjacent the tail of the "centering" cam 42, will cause each particular foot 35, suspended initially vertically removed from the material therebelow, first gradually and until the point 44 is 125 reached to progressively compress to the predetermined extent the said material, and thereafter gradually and until the point 43 is reached to release the pressure upon said material. A general indication of the pres- 130

ent lay of one-half of the fixed circumferential groove 30, formed as aforesaid in the anchored cam 31, is shown by the dotted line elevation 30' of Fig. 3; and from an examination of which the description of the action of each foot 35 with relation to the locations of the points 43 and 44 of Fig. 2 will be better understood.

Now passing to a description of the operation of the latch 72 and of the parts controlled thereby, and advertizing preliminarily to a description of said parts so controlled by the actuation of said latch, attention is directed particularly to Figs. 2 and 3. It should first be understood that main driving shaft 18 as disclosed in Fig. 2 is assumed to have been rotated one quarter of a revolution to take up the position illustrated in Fig. 3, whereby the keyway 45 may be observed in plan in both said figures. Said key-way is adapted to accommodate the feather 46 slidably therein. Feather 46 is flush with the circumference of the shaft 18 and is fastened by means of screws 47 (Fig. 25 3) to a sliding collar 48 loosely mounted on said shaft. In the outer portion of collar 48 is formed an annular groove 49, arranged to receive the pair of oppositely disposed studs 50 one of which is illustrated in said Fig. 3; each of said studs extending inwardly from one of the two lower arms of the bifurcated lever 51, which is fulcrumed upon stud 52 extending from arm 53 to bracket 54. Driving shaft 18 finds a bearing in the collar portion 54' formed integrally upon the bracket 54; said bracket also carrying an integral extension 54''. Lever 51 has mounted upon its upper end a segment 55 carrying the pins 56 and 57; these parts being provided for a purpose which will be explained hereinafter, to wit, to allow a rod 64 hereinafter mentioned to control the rocking of lever 51, controlling the feather 46 (Fig. 3).

The free end of the feather 46 has a raised portion 58 adapted at the proper times to function as a cam. Clutch case 20 is here bolted as shown to the driving pulley 19, which latter is loosely mounted upon driving shaft 18 but restrained against longitudinal movement thereon by virtue of its interposition between the collar 59 fixedly mounted upon said shaft 18 and the clutch head 60 also fixedly mounted upon said shaft. Pivottally mounted upon the inner face of said clutch head 60 is a pawl 61 adapted to engage with one of a plurality of lugs 62 (only one being here shown) extending from the inner face of clutch case 20. With the feather 46 in normal location within key-way 45 the cam portion 58 lies in the position illustrated in Fig. 3, that is, in such an effective location that upon the driving of pulley 19 in the direction of the arrow shown on driving pulley 21, the clutch

case 20 carried therewith will bring one of said lugs formed in said clutch case into engagement with pawl 61 and couple to said driving pulley the pulley-carrying clutch head 60 and consequently also couple to said driving pulley the driving shaft 18. The dotted-line position of said cam portion 58 shown in this figure at 58' in connection with its coöperating parts clarifies the above disclosure, and makes clear the statement contained hereinafter in connection with the description of the operation of the apparatus that the predetermined movement of feather 46 in the direction of the arrow 63 within key-way 45, due to the rocking of lever 51, breaks the coupling of driving pulley 19 and driving shaft 18.

Before passing now to a consideration of Figs. 1 and 2, in continuation of this description of the operation of the latch 72 and of the parts controlled thereby, attention is preparatorily called to the location in Figs. 2 and 3 of the segment 55 and the pins 56 and 57 carried thereby, as just mentioned in connection with Figs. 2 and 3. Referring to said Figs. 1 and 2, free to slide in extension 54'' of bracket 54 is a square rod 64, and this rod is supported at its front end within the bracket 65 mounted upon the fixed supporting piece 66. Beyond the bracket 65 the front end of this rod 64 is bent into a handle 67 for manual control of said segments as hereinafter described. Opposite segment 55 is arranged a block 68 (Fig. 2), fixedly attached to the rod 64 whereby upon the shifting of said rod said block may move in the path of the pins 56 and 57. A retractile spring 69, extensible between the hook 70 mounted as shown and the collar 71 fixedly mounted upon said rod, tends to urge the rod 64 to its rear position (as just described in connection with Fig. 3), but is normally prevented from forcing said rod toward the front end of the apparatus by the normal engagement of the aforementioned latch 72 with the notch 73 formed in the rod 64. The latch 72 is slidably mounted upon supporting piece 66 as by means of the slots 74 and the guiding screws 75, as best shown in Fig. 1, and normally urged to locking position with the said notch 73 by means of the retractile spring mounted as shown in Fig. 2; and is provided with a nose portion 72' adapted here to project to the extent shown into the possible path of a projecting container 8 or a unit mass of material during the rotation of turret 24. The purpose of providing this latch 72 and its nose portion 72' is to disclose a means capacitated for automatically causing a cessation of operation of the apparatus whenever container 8 or a unit mass of material is so defectively fed upon rotating table 13 that the cam 42 mentioned in the following paragraph cannot correct the defect, and to

that end to arrange said latch 72 whereby an untoward engagement with it by a container 8 or a unit mass of material will cause said latch to disengage with the rod 64 sufficiently to allow said rod (as herein-after described) to uncouple the driving pulley 19 and the driving shaft 18, thereby to bring about a halting of the turret 24.

The cam 42 is mounted here upon the bed-
10 plate 9, preferably placed as shown and at such an angle as to gradually engage with a possibly projecting container 8 or a unit mass of material which is yet not projecting sufficiently to engage with the nose 72' of the
15 latch 72 to properly force said container or said mass of material into proper location below the appropriate foot 35 suspended thereover.

Referring now particularly to Figs. 1, 2
20 and 4, a substantially Z-shaped lever 77 is shown, its goose-neck portion being medially accommodated within the slot 78 formed in the bed plate 9, said lever being pivotally mounted as at 79 and carrying a fixedly
25 mounted claw 80. On the underside of rotating table 13 is a depending octuple-notched cam 81, one notched section of said cam being preferably located as shown beneath each of the subdivisions 22 located as aforesaid upon
30 the upper surface of said rotating table. Lever 77 is provided with an extension 82 (Fig. 4), carrying as shown a roller 83 which is constantly urged into contact against the outer irregular wall of cam 81
35 as by means of the retractile spring 84 connected at one end as shown to said claw 80 and at its other end to an anchor pin 85 carried by the bed plate 9. Lever 77 is provided as shown with the ears 86, between which are pivotally mounted a lever 87 carrying at one end a dog 88, by gravity urged to the location shown in Fig. 1, and carrying at its other end a nose 89 adapted to contact with the curved wall 90 mounted
40 as illustrated upon the upper surface of bed plate 9, said wall 90 preferably coinciding with an arc constructed from a center coincident with the pivotal center adjacent the point 79 of lever 77. Wall 90 carries as
45 shown cam plates 91 and 92, said wall being supported upon the standards 93. A hook 94 (Fig. 1) preferably constructed of resilient material and having a terminal tooth 94', is fixedly mounted upon the lever
50 77 as by means of the screws 95 (said Fig. 1).

Having thus described this embodiment of this invention, the operation thereof, which should largely be obvious, is substantially as follows. The handle 67 of the square rod 64 is manually or otherwise urged to the rear of the apparatus in the direction of the arrow 96 (Fig. 2), thereby causing the block 68 to engage with the pin
65 57 of the segment 55 (Figs. 2 and 3), and

thus rocking the lever 51, which in turn shifts in the direction of the arrow the collar 48 fixedly mounted upon the feather 46 as aforesaid (Figs. 2 and 3). The feather 46 will thus carry the cam portion 58 to the 70 location illustrated in Fig. 3 and in this manner set up a coupled relation as described above between clutch case 20 and clutch head 60. Said clutch case is as aforesaid fixedly mounted upon driving pulley 75 19 (which is here assumed to be receiving drive from the belt 21) and the clutch head is fixedly mounted as aforesaid upon the main driving shaft 18. Main driving shaft 18 as aforesaid drives the worm gear 16 and consequently its supported rotating table 13 and turret 24. With said table and said turret so rotating, successive unit masses of material or containers 8 are manually or otherwise fed into each of the subdivisions 22 as aforesaid, and as each of these subdivisions progressively passes the feeding point 6 (Fig. 2) during the rotation of table 13 and turret 24 subsequent to the feeding upon said table of each container or mass of material, the appropriate foot 35 is caused gradually to descend and ascend, as aforesaid and in accordance with the lay of the cam groove 30 (Fig. 3) with reference to the particular mass of material or container therebelow supported upon the rotating table 13. It will be seen that after the rotation of said table 13 has sufficiently progressed to have fed upon each subdivision 22 a mass of material or container 8, 85 thereafter during the rotation of said table each mass of material directly supported upon said table 13 or within a container 8 will receive gradually increasing compression between the points 43 and 44 (Fig. 2), 90 and that consequently all of said masses of material will simultaneously be subjected to the compressing action of its appropriate foot 35 in accordance with the particular location of their supporting subdivisions 22 95 100 somewhere between said points 43 and 44. Should any of said unit masses of material or containers 8 be projecting within a predetermined degree, preferably to a degree 105 such that upon contacting the "centering" 110 cam 42 said cam will during the subsequent rotation of table 14 properly force toward the center of said table said unit mass of material or said container 8 sufficiently to properly dispose upon the proper subdivision 22 said mass of material or said container, said cam will, by virtue of the projecting mass of material or container clearing the nose portion 72' of the latch 72, be 115 enabled to function as just stated (Fig. 2). 120 The rotation of table 13 then carries each successive mass of material or container 8 toward the location of the hook 94. Upon said table advancing to a suitable position whereby said mass of material or said con- 125 130

tainer 8 lies just underneath the tooth 94 (Fig. 1) of said hook, the roller 83 (Fig. 4) is lying substantially as shown within the trough of one of the notches carried by the cam 81. Upon the table 13 rotating farther in its normal direction, roller 83 rides away from the center of said table 13 and in the direction of the arrow 83' along the wall 81' of said cam 81, thereby, and before table 13 has farther rotated to remove from within range of said hook the mass of material or container now being considered, engaging with said mass of material or said container, and, due to the differences in leverage, quickly causing the rocking of lever 77 upon its pivot 79 and withdrawing from the subdivision 22 and onto the bed-plate 9 said mass of material or said container engaged thereby (Fig. 4). It should be understood that during this ejection of said mass of material or container 8 (Figs. 1 and 4) the preferably resilient hook 94 is downwardly deflected to the abnormal position disclosed in Fig. 1, by means of the engagement of the nose 89 of the dog 88 with the underside of cam 91, until said lever 77 has been so far swung outwardly on its pivot 79 as to allow said nose 89 to ride upwardly on the under curved surface 91' of said cam 91 or totally clear said cam and ride along the upper curved surface of cam 92; whereupon dog 88 will allow hook 94 to strain upwardly to normal position and away from its previous engagement with said container. It should also be understood that before the operation just described, and as rotating table 13 advances so far as to bring a mass of material or a container 8 just within range of said hook 94, said roller 83 (Fig. 4) has just left the illustrative point 81'' of the cam 81 and is advancing in the direction of the arrow 83'' along the wall of said cam 81 parallel to said arrow 83'', thereby advancing the tooth upon said hook 94 toward the center of table 13 whereby said hook may enter into a preferable latch engagement with said mass of material or a portion of said container 8.

It will be seen from the conformation of the wall of cam 81 parallel to the arrow 83'' that the just described actuation of hook 94 takes place very rapidly in comparison with the interval of time required to transport to without the range of said hook a mass of material or container 8.

Reverting now to the parts shown in Fig. 2 adjacent the cam 42, it is obvious that were a mass of material or a container 8 fed adjacent the point 6 to a subdivision 22 upon rotating table 13 in such careless or erroneous manner as to cause said mass of material or container 8 to project to such a great extent as to prevent the proper functioning of said cam 42, a jamming of the parts and

stoppage or breaking of the apparatus would probably occur. In order to satisfy this contingency, there is provided the latch 72, mounted as aforesaid and maintained by means of the spring 76 normally in such manner that it is in locking engagement with the notch 73 formed upon the square rod 64 (such normal engagement being due as aforesaid to the initial shift of said rod 44 in the direction of the arrow 96 to couple as aforesaid to the driving pulley the driving shaft 18); the latch 72 being provided as aforesaid with a nose 72' in such location that said nose 72' will be engaged by a projecting mass of material or container 8 provided such mass of material or container is projecting to such a degree as will not permit of the proper functioning of cam 42. Upon such mass of material or container projecting as thus described from a subdivision 22, said mass of material or container will in an obvious manner and after an obvious fraction of rotation of table 13, engage with nose 72' of latch 72, and shift said latch against the tension of spring 76 in the direction of the arrow 72'', break the engagement between said latch and the notch 73 formed upon the square rod 64, and allow the retractile spring 69 (Fig. 2) to destroy the theretofore coupled engagement of driving shaft 18 with driving pulley 19 as shown in Fig. 3.

It will thus be seen that I have provided an embodiment of this invention well adapted to attain the various ends and objects thereof and an embodiment also capable of inexpensive manufacture, accuracy and rapidity of operation, and simplicity of control.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention, which, as a matter of language, might be said to fall therebetween.

Having described my invention, what I claim as new and desire to secure by Letters Patent is:

1. In apparatus of the class described, in combination, means carrying a plurality of compartments each adapted to support a mass of material, compressing means normally bodily removed from one of said compartments, and means adapted to cause the simultaneous travel of the first-mentioned

means and said compressing means whereby said compressing means bodily enters one of said compartments.

2. In apparatus of the class described, in combination, means adapted to support a mass of material, compressing means normally removed from said material, means adapted to cause the simultaneous travel of said supporting means and said compressing means whereby said compressing means acts upon said material, and alining means adapted predeterminedly to act upon said material.

3. In apparatus of the class described, in combination, rotary means carrying a plurality of compartments each adapted to support a mass of material, compressing means normally bodily removed from one of said compartments and carried by said rotary means, and means adapted during the rotation of the first mentioned means to cause said compressing means bodily to enter the compartment last-mentioned.

4. In apparatus of the class described, in combination, rotary means carrying a plurality of compartments each adapted to support a mass of material, compressing means normally bodily removed from one of said compartments and carried by said rotary means, and means adapted during the rotation of the first mentioned means to cause said compressing means bodily to enter the compartment last-mentioned and thereafter to traverse said compartment with gradually increasing effect.

5. In apparatus of the class described, in combination, rotary means adapted to support a mass of material, said rotary means carrying a plurality of material-accommodating subdivisions into each successive one of which a mass of material may be fed during the rotation of said means, a plurality of compressing means each carried by said rotary means adjacent but normally entirely removed from one of said subdivisions, and means adapted during said rotation to cause each of said plurality of compressing means successively bodily to enter said subdivisions.

50 6. In apparatus of the class described, in combination, rotary means adapted to support a mass of material, said rotary means carrying a plurality of material-accommodating subdivisions into each successive one of which a mass of material may be fed during the rotation of said means, a plurality of compressing means each carried by said rotary means adjacent but normally entirely removed from one of said subdivisions, and means adapted during said rotation to cause each of said plurality of compressing means successively bodily to enter said subdivisions.

65 7. In apparatus of the class described, in combination, rotary means adapted to sup-

port a mass of material, said rotary means carrying a plurality of material-accommodating subdivisions into each successive one of which a mass of material may be fed during the rotation of said means, a plurality of compressing means each carried by said rotary means adjacent but normally entirely removed from one of said subdivisions, means adapted during said rotation to cause each of said plurality of compressing means successively bodily to enter said subdivisions but with varying effect adjacent certain different ones of said subdivisions, and means adapted to pull the material from each of said subdivisions when it has been carried to a predetermined point, said ejection means being controlled by the rotation of said rotary means.

8. In apparatus of the class described, in combination, rotary means adapted to support a mass of material, said rotary means carrying a plurality of material-accommodating subdivisions into each successive one of which a mass of material may be fed during the rotation of said means, a plurality of compressing means each carried by said rotary means adjacent one of said subdivisions, means adapted during said rotation to cause said plurality of compressing means to act simultaneously upon material accommodated within said subdivisions, and means adapted to cause a halting of the rotation of said rotating means when engaged by incorrectly accommodated material being transported by said rotating means.

9. In apparatus of the class described, in combination, rotary means adapted to support a mass of material, said rotary means carrying a plurality of material-accommodating subdivisions into each successive one of which a mass of material may be fed during the rotation of said means, a plurality of compressing means each carried by said rotary means adjacent one of said subdivisions, means adapted during said rotation to cause said plurality of compressing means to act simultaneously upon material accommodated within said subdivisions, means adapted to cause a halting of the rotation of said rotating means when engaged by incorrectly accommodated material being transported by said rotating means, and alining means adapted predeterminedly to act upon said incorrectly accommodated material provided said material is not so incorrectly accommodated as to engage with said halting means.

10. In apparatus of the class described, in combination, means adapted to support a mass of material, compressing means normally removed from said material, and means adapted to cause the simultaneous travel of said supporting means and said compressing means whereby said compressing means acts upon said material, said com-

pressing means including a presser member and an angularly offset member for aiding said material in withstanding internal pressure.

- 5 11. In apparatus of the class described, in combination, means carrying a compartment adapted to support a mass of material, means carrying a horizontally arranged surface predeterminedly located, compression 70
10 means normally adjacent said compartment, means adapted to actuate said compression means to act upon the material within said compartment to compress said material and means adapted predeterminedly to transfer 75
15 said mass from said compartment on to said surface.

12. In apparatus of the class described, in combination, means carrying a compartment adapted to support a mass of material, compression means normally adjacent said compartment, means adapted to actuate said compression means to act upon the material within said compartment to compress said material and means adapted to eject said 80
20 mass from said compartment substantially horizontally; the means last-mentioned including a container which is removably carried by said compartment and which is adapted directly to support said mass of material 85
25 therein.

- 30 13. In apparatus of the class described, in combination, means carrying a compartment adapted to support a mass of material, compression means normally adjacent said compartment, means adapted to actuate said compression means to act upon the material within said compartment to compress said material and means adapted to eject said mass from said compartment substantially 90
35 horizontally; the means last-mentioned including a container which is removably carried by said compartment and which is adapted directly to support said mass of material 95
40 therein; said compartment being provided with a substantially horizontally arranged way for the accommodation of a portion of said container.

- 45 14. In apparatus of the class described, in combination, means carrying a compartment adapted to support a mass of material, compression means normally adjacent said compartment, means adapted to actuate said compression means to act upon the material within said compartment to compress said material and means adapted to eject said mass from said compartment substantially 100
50 horizontally; the means last-mentioned including a container which is removably carried by said compartment and which is adapted directly to support said mass of material 105
55 therein; said compartment being provided with a substantially horizontally arranged way for the accommodation of a portion of said container.

- 60 15. In apparatus of the class described, in combination, means carrying a compartment

adapted to support a mass of material, compression means normally adjacent said compartment, means adapted to actuate said compression means to act upon the material within said compartment to compress said material and means adapted to eject said mass from said compartment substantially horizontally; the means last-mentioned including a container which is removably carried by said compartment and adapted directly to support said mass of material therein; said compartment being provided with an undercut groove for the accommodation of a portion of said container.

16. In apparatus of the class described, in combination, means carrying a compartment adapted to support a mass of material, compression means normally adjacent said compartment, means adapted to actuate said compression means to act upon the material within said compartment to compress said material and means adapted to eject said mass from said compartment substantially horizontally; the means last-mentioned including a container which is removably carried by said compartment and which is adapted directly to support said mass of material therein; said compartment being provided with a slide-way for the accommodation of a projection carried by said 95
90 container.

17. In apparatus of the class described, in combination, means carrying a compartment adapted to support a mass of material, compression means normally adjacent said compartment, means adapted to actuate said compression means to act upon the material within said compartment to compress said material and means adapted to eject said mass from said compartment substantially 100
105 horizontally; the means last-mentioned including a container which is removably carried by said compartment and which is adapted directly to support said mass of material therein and also including an instrumentality adapted to engage said container 110
115 and pull the same from said compartment.

18. In apparatus of the class described, in combination, means carrying a compartment adapted to support a mass of material, compression means normally adjacent said compartment, means adapted to actuate said compression means to act upon the material within said compartment to compress said material, said compartment being open at one end and said compression means including a compressing-plate and a wall adapted to close the open end of said compartment during the compressing operation.

19. In apparatus of the class described, means carrying a compartment adapted to support a mass of material, compressing means normally adjacent said compartment, means adapted to actuate said compressing means to compress the material within said 125
130

compartment; in combination with a removable container for accommodation within said compartment, said compartment and said container having mutually coöperant conformations.

20. In apparatus of the class described, means carrying a compartment adapted to support a mass of material, compressing means normally adjacent said compartment, means adapted to actuate said compressing means to compress the material within said compartment; in combination with a removable open-topped container for said compartment, into which container said compressing means may advance.

21. In apparatus of the class described, means carrying a compartment adapted to support a mass of material, compressing means normally adjacent said compartment, means adapted to actuate said compressing means to compress the material within said compartment; in combination with a removable open-topped container for accommodation within said compartment and into which container said compressing means may advance; said container and said compartment carrying coöperating conformations whereby said container may be horizontally slid into and from said compartment.

22. In apparatus of the class described, in combination, means carrying a compartment adapted to support a mass of material, compressing means normally adjacent said compartment, means adapted to actuate said compressing means to compress the material within said compartment, and alining means adapted predeterminedly to act upon said material, said alining means including a member adapted to wipe into said compartment a container which substantially horizontally projects therefrom.

23. In apparatus of the class described, means carrying a compartment adapted to support a mass of material, compressing means normally adjacent said compartment, means adapted to actuate said compressing means to compress the material within said compartment; in combination with a removable open-topped container for accommodation within said container and into which container said compressing means may advance; said container and said compartment carrying coöperating conformations whereby said container may be horizontally slid into and from said compartment; and alining means adapted predeterminedly to act upon said material, said alining means including a member adapted to force predeterminedly within said compartment a container which horizontally projects therefrom.

24. In apparatus of the class described, in combination, means carrying a compartment adapted to support a mass of material, com-

pressing means normally adjacent said compartment, means adapted to actuate said compressing means to compress the material within said compartment, a removable container for accommodation within said compartment thereby directly to support said mass, and alining means adapted predeterminedly to act upon said material, said alining means including a member adapted to wipe into said compartment a container which substantially horizontally projects therefrom; said member being resiliently urged to a predetermined set.

25. In apparatus of the class described, means carrying a compartment adapted to support a mass of material, compressing means normally adjacent said compartment, means adapted to actuate said compressing means to compress the material within said compartment, in combination with a removable open-topped container adapted for accommodation with said compartment into which container said compressing means may advance; said container and said compartment carrying coöperating conformations whereby said container may be horizontally slid into and from said compartment; and alining means adapted predeterminedly to act upon said material, said alining means including a member adapted to force predeterminedly within said compartment a container which horizontally projects therefrom; said member being resiliently urged to a predetermined set.

26. In apparatus of the class described, in combination, a movable member which is adapted to move past a predetermined point, a plurality of substantially horizontal tracks carried by said member, a removable container adapted to be advanced over said tracks when said member is adjacent said predetermined point, and a compressing instrumentality adapted to advance toward the interior of said container.

27. In apparatus of the class described, in combination, a movable member which is adapted to move past a predetermined point, a plurality of substantially horizontal tracks carried by said member, a removable container adapted to be advanced over said tracks when said member is adjacent said predetermined point, and a compressing instrumentality adapted to advance toward the interior of said container; said compressing instrumentality being operatively connected with guiding means which causes a predetermined bodily removal of said instrumentality from the interior of said container and a predetermined advance of said instrumentality toward the interior of said container.

28. In apparatus of the class described, in combination, a movable member which is adapted to move past a predetermined point, a plurality of substantially horizontal tracks

- carried by said member, a removable container adapted to be advanced over said tracks when said member is adjacent said predetermined point, and a compressing instrumentality adapted to advance toward the interior of said container; said compressing instrumentality being operatively connected with guiding means which causes a predetermined bodily removal of said instrumentality from the interior of said container and a predetermined advance of said instrumentality toward the interior of said container; said guiding means including a cam.
- 5 29. In apparatus of the class described, in combination, a movable member which is adapted to move past a predetermined point, a plurality of substantially horizontal tracks carried by said member, a removable container adapted to be advanced over said tracks when said member is adjacent said
- 10 predetermined point, and a compressing instrumentality adapted to advance toward the interior of said container; said compressing instrumentality being operatively connected with guiding means which causes a predetermined bodily removal of said instrumentality from the interior of said container and a predetermined advance of said instrumentality toward the interior of said container; said guiding means including a cam-groove, a roller coöperating therewith and a connection between said roller and said instrumentality.
- 15 In witness whereof I have hereunto signed my name in the presence of two witnesses.
- 20

SIMON COOPER.

In the presence of—

A. M. HENRY,
A. L. MILLER.
